FOLDING CHAIR

Glen J. Arthur, Davenport, Iowa

Application September 22, 1937, Serial No. 165,138

2 Claims. (Cl. 155—127)

My present invention relates to folding nursery chairs and is in the nature of an improvement upon the structure shown in my Patent No. 1,910,736, issued May 23, 1933. Inasmuch as the construction in the center of the seat of the chair has not been essentially changed, I have refrained from illustrating this in the present drawing, it being possible to determine this construction from my prior patent. The present invention pertains more particularly to the locking mechanism for the tray and the latch for holding the chair against accidental folding.

Among the objects of this invention are to provide improved means for latching the tray in position on the chair arms; to provide improved means for latching the back to one of the arms so as to prevent inadvertent collapsing of the chair; and such further objects, advantages, and capabilities as will hereafter appear and as are inherent in the construction disclosed herein.

In the drawing annexed hereto and forming a part hereof,

Fig. 1 represents a side elevation of my improved chair in assembled and latched position, ready for use;

Fig. 2 represents this chair with the tray in position ready to be placed on the arms and secured in place thereon;

Fig. 3 represents a fragmentary edge view of one end of the tray and illustrating the projection from the bottom of the tray which cooperates with an arm in holding the tray in position thereon.

I shall now refer in greater detail to the annexed drawing for a more complete description of this invention. A pair of loops 1 and 2, hinged together at 3 form the legs for supporting the seat 4. The ends of the loop 1 are pivotally connected by a pair of bolts 5 which also connect the uprights 6 of the back 7 to the seat 4. A pair of arms 8 are pivotally connected at 9 to the uprights 6 and at 10 to the posts 11. The lower ends of these posts 11 are pivotally connected at 12 to the seat 4, the pivot points 5, 9, 10, and 12 forming the angles of a parallelogram. A stud 13 projects laterally from one of the uprights 6 and is designed to be engaged by the notch 14 in the latch member 15. It will therefore be apparent that when the latch member 15 is engaged, as shown in Fig. 1, the chair will be held from collapsing unintentionally.

A tray 16 has downwardly projecting elements 17 which engage outside of the arms 8 and are provided with inward extensions 18 which engage under the arms. These downward projec-

tions 17 guide the tray with respect to the arms 8 and the extensions 18 abut against the forward side of the posts 11 when the tray is shoved back into its proper position. Projections 19 extend forwardly and upwardly from the posts 11 and engage in front of the extensions 18 when the chair is completely set up, as illustrated in Fig. 1. From the foregoing it is apparent that when the chair is assembled and set up, as in Fig. 1, with the latch member 15 engaging the stud 13, as shown in this figure, it will be impossible to remove the tray 16 without bending or breaking some part of the chair, unless the latch 15 is first disconnected from the stud 13.

When it is desired to use the upper part of the chair with a toilet seat, the nuts may be removed from the bolts 5 and the legs detached so that downward projections 4a and 4b from the seat 4 may fit within the opening in the toilet seat and hold the two against any substantial relative movement. The opening in the chair seat has not been shown in the present drawing since it does not differ essentially from that shown in my prior patent referred to above.

While I have disclosed what is now regarded as the preferred embodiment of this invention, I desire this disclosure to be regarded as illustrative only and not to be interpreted in a limiting sense.

Having now described my invention, I claim:

1. A folding chair comprising in part a seat member having a back pivotally connected thereto to swing forwardly and backwardly with respect to the seat, into open and folded condition, arms pivotally connected to the back and extending above and substantially parallel to the sides of the seat, posts pivotally connecting the forward end portions of the arms to the sides of the seat member, and a tray slidable on the arms and having downwardly projecting elements having laterally extending ends to engage the arms and guide the tray with respect thereto, said ends being slidable along the under side of said arms into engagement with said posts, and said posts having projections extending forwardly therefrom and upwardly into positions in front of said ends whereby to prevent the tray from being removed from the arms.

2. A folding chair comprising in part a seat member having a back pivotally connected thereto to swing forwardly and backwardly with respect to the seat, into open and folded condition, arms pivotally connected to the back and extending above and substantially parallel to the sides of the seat, posts pivotally connecting the forward end portions of the arms to the sides of

the seat member, a tray slidable on the arms and having downwardly projecting elements having laterally extending ends to engage the arms and guide the tray with respect thereto, said ends being slidable along the under side of said arms into engagement with said posts, and said posts having projections extending forwardly therefrom and upwardly into positions in front of said ends whereby to prevent the tray from being re-

5 moved from the arms, a latch member pivotally connected to an arm and provided with a slot for engagement with a cooperating stud, and a stud projecting from one edge of the back and arranged to be received in said notch and to co-operate with said latch member in holding the chair against folding.

GLEN J. ARTHUR.
